Primary Examiner — Patricia Palasik(74) *Attorney, Agent, or Firm* — Ann M. Knab; Thad McMurray(57) **CLAIM**

The ornamental design for a firing plate for a dental furnace, as shown and described.

DESCRIPTION

FIG. 1 is a perspective view of a firing plate for a dental furnace, showing our new design;

FIG. 2 is a top plan view thereof;

FIG. 3 is a bottom plan view thereof;

FIG. 4 is a front view thereof;

FIG. 5 is a rear view thereof;

FIG. 6 is a left side view thereof; and

FIG. 7 is a right side view thereof;

FIG. 8 is a perspective view of a second embodiment of our new design;

FIG. 9 is a top plan view thereof;

FIG. 10 is a bottom plan view thereof;

FIG. 11 is a front view thereof;

FIG. 12 is a rear view thereof;

FIG. 13 is a left side view thereof; and,

FIG. 14 is a right side view thereof.

The broken line showing is for illustration purposes only and forms no part of the claimed design.
